UNITED STATES PATENT OFFICE.

CHARLES B. HOY AND CHARLES KOBMANN, OF CINCINNATI, OHIO.

GARMENT-CLASP.

No. 799,906.

Specification of Letters Patent.

Patented Sept. 19, 1905.

Application filed May 19, 1905. Serial No. 261,161.

To all whom it may concern:

Be it known that we, CHARLES B. HOY and CHARLES KOBMANN, citizens of the United States, residing at Cincinnati, in the county of Hamilton and State of Ohio, have invented 5 certain new and useful Improvements in Garment-Clasps, of which the following is a specification.

Our invention relates to improvements in 10 garment-clasps. One of its objects is to provide an improved pivot garment-clasp adapted for use on garters, suspenders, and similar articles.

Another object is to provide a clasp of the 15 above character in which the members may be clasped and unclasped, in which the members will move relative to each other with a minimum amount of friction, and which is not liable to become accidentally unclasped.

20 It further consists in certain details of form, combination, and arrangement, all of which will be more fully set forth in the description of the accompanying drawings, in which—

Figure 1 is a plan view of one of the clasp 25 members. Fig. 2 is a central section through the same on line *v v* of Fig. 1. Fig. 3 is a plan view of the opposite clasp member. Fig. 4 is a central section through the same on line *aa* of Fig. 3. Fig. 5 is a plan view of the 30 two members in the clasped position, being modified by the omission of two of the slots *a*. Fig. 6 is a section through the same on line *ww* of Fig. 5. Figs. 7, 8, and 9 are views similar to Figs. 1, 2, and 3, showing a modification, 35 Figs. 7 and 8 showing the reverse side from Figs. 1 and 5. Fig. 10 is a view, similar to Fig. 5, of another modification.

A and B, Figs. 1 to 6, represent, respectively, the opposite clasp member of a garter. 40 The member A is provided with slots *a* for the attachment of the elastic ribbon. The number of slots *a* is immaterial, four being shown in Fig. 3, while only two are shown in Figs. 5, 8, and 10.

45 D represents a tongue stamped so as to project up from one face of member A.

Member B has a slot *b* for attachment of the elastic ribbon.

C represents a slot formed by removing a 50 portion of the metal, through which the tongue D may be projected.

E represents a semicircular rib stamped from the member B.

The metal is severed at *e e'* from slot C to 55 ward slot *b*, thereby forming a spring finger

or tongue F, which is slightly raised from the face of member B.

The parts are so proportioned that when united the tongue D rests at its forward edge against the rib E and forms a rocking pivot 60 or knife-edge bearing therewith, the circumference of edge *d* being less than that of rib E. The finger F during the introduction of tongue D bears upon its upper surface and after its introduction springs down in rear of 65 tongue D sufficiently to prevent its ready or accidental retraction. If desired, a further projection *d'* may be formed on the tongue D to prevent any tendency of the parts becoming accidentally unclasped by reason of the increased force required to pass the projection *d'* beneath the spring-finger. The slot C is of sufficient length to permit the desired rocking or pivotal movement of the members, while the rocking or knife-edge bearing insures a minimum amount of friction. The tongue D holds the faces of the two members close to each other, and there are no projections liable to catch the garments. The parts are simple in form and readily formed at a 70 single operation by stamping from sheet metal.

In the modification Figs. 7, 8, and 9 the rocker or knife-edge bearing is formed between the point G on member B and the base of the tongue D' on the member A instead of 75 as shown in Figs. 1 to 6. In this form the end *d'* of tongue D' is shorter, so as not to contact with rib E'.

In the modification Fig. 10 the rib E' has a projection E'', and the tongue D' is notched 80 at its forward end, so as to form a rocker or knife-edge bearing with the projection E''.

The mechanism herein specified is capable of considerable modification without departing from the principle of our invention. 85

Having described our invention, what we claim is—

1. In an article of the character indicated, a clasp member having a raised tongue and an engaging member having a raised rib, to occupy a position in front of the tongue, a slot to receive said tongue, and a spring-finger to engage the rear end of the tongue to retain the tongue in the engaged position. 100

2. In an article of the character indicated a clasp member having a raised tongue, an engaging member having a slot to receive said tongue, and a spring-finger to engage the rear end of the tongue to retain the tongue in position, and a knife-edge or rocking bearing 105

between the tongue and the last-named member.

3. In an article of the character indicated a clasp member having a raised tongue, an engaging member having a raised rib to partially encircle said tongue, a slot for the passage of the tongue, and a knife-edge or rocking contact between the tongue and raised rib.

4. In an article of the character indicated a clasp member having a raised tongue, an engaging member having a raised rib to partially encircle the tongue, a slot for the passage of the tongue, a spring-finger to retain the tongue in place and a knife-edge or rocking contact between the tongue and raised rib.

5. In an article of the character indicated a clasp member having a raised tongue, an engaging member having a raised rib in front

of the tongue, a slot for the passage of the tongue and a knife-edge or rocking contact 20 between the tongue and raised rib.

6. In an article of the character indicated a clasp member having a raised tongue, an engaging member having a raised rib in front of the tongue, a slot for the passage of the 25 tongue and a knife-edge or rocking contact between the tongue and said last-named member.

In testimony whereof we have affixed our signatures in presence of two witnesses.

CHARLES B. HOY.

CHARLES KOBMANN.
